UNITED STATES PATENT OFFICE.

ERASTUS W. ROGERS, OF DURHAM, NORTH CAROLINA.

ATTACHMENT FOR STOVES.

1,395,523.

Specification of Letters Patent.

Patented Nov. 1, 1921.

Application filed May 10, 1920. Serial No. 380,211.

To all whom it may concern:

Be it known that I, ERASTUS W. ROGERS, a citizen of the United States, residing at Durham, in the county of Durham and State 5 of North Carolina, have invented a new and useful Attachment for Stoves, of which the following is a specification.

This invention relates to an attachment for stoves whereby the capacity of a cook 10 stove can be greatly increased by distributing the heat from one or two burners of an oil stove, gas stove or the like to two or more openings in the attachment and over which utensils can be placed.

15 A further object is to provide an attachment of this character which can be used in connection with either gas stoves, oil stoves, wood stoves or the like, it being possible easily to apply the device to a stove and 20 there being means for controlling the flow of hot gases through the attachment so that the desired result can be obtained.

Another object is to provide with the attachment a warming tray adapted to be supported by the attachment beyond one side 25 of the stove on which the attachment is mounted.

With the foregoing and other objects in view, which will appear as the description 30 proceeds, the invention resides in the combination and arrangement of parts and in the details of construction hereinafter described and claimed, it being understood that, within the scope of what is claimed, 35 changes in the precise embodiment of the invention shown can be made without departing from the spirit of the invention.

In the accompanying drawings the preferred form of the invention has been shown.

40 In said drawings—

Figure 1 is a front elevation of the attachment.

Fig. 2 is a plan view thereof.

Fig. 3 is a horizontal section.

45 Fig. 4 is a longitudinal section.

Referring to the figures by characters of reference 1 designates the base of the attachment, the same being provided, in the present instance, with an opening 2 near one end thereof over which may be supported one or more covering plates 3 having depending heat conducting tubes 4. The housing 5 of the attachment is indicated at 5 and is mounted on and suitably secured to the 50 base, this housing being provided with outlet openings 6 for the escape of hot gases.

In the present instance four of these openings have been shown, two being located adjacent each end of the attachment. The housing may also be provided in its top 60 with a transverse outlet slot 7 adapted normally to be closed by means of a slide 8.

Arranged longitudinally upon the base 1 is a partition 9 which divides the interior of the housing 5 into two noncommunicating 65 compartments 10 and 11, two of the openings 6 communicating with each compartment and one of the openings 2 communicating with each compartment. One of the end walls of the housing 5 can be provided with 70 an outlet opening 12 communicating with both compartments. A sliding damper 13 is mounted in said end portion of the housing and can be shifted by means of a handle 14 so as to open or close the outlet 12. 75 This outlet may open directly to the external atmosphere or can open into a smoke pipe connected to a chimney or the like. It is not considered necessary to illustrate such an arrangement. 80

A rod 15 is extended transversely through the compartments 10 and 11 and has dampers 16 secured to it. These dampers are adapted to be turned by means of a rod so as to close the compartments 10 and 11 close 85 to the adjacent outlet openings 6 thus to deflect the hot products of combustion from said compartments 10 and 11 into the outlet openings 6 adjacent the dampers 16.

Another transverse rod 17 extends across 90 the compartments 10 and 11 at a point adjacent the center of the housing and this rod has dampers 18 secured thereto and within the respective compartments. By rotating the rod the dampers can be raised or 95 lowered in the compartments. When they are raised they will cut off communication between the openings 2 and those openings 6 remote therefrom. Consequently products of combustion will flow directly from the 100 openings 2 to the openings 6 thereabove so that only two of the outlet openings 6 can thus be utilized for cooking purposes.

Supporting plates 19 are arranged upon the base 1 adjacent that end thereof remote 105 from the openings 2 and slidably mounted on and supported by these plates is a warming pan 20 which can be readily moved to or from position under the base 1 by means of a handle 21.

110 Suitable attaching means indicated generally at 22 can be provided at the ends of

the base 1 for securing the attachment to a stove. It is desired when the attachment is in position to have the openings 2 directly over the burners of the stove while the warming pan 20 will be supported beyond the side of the stove. The hot products of combustion will ascend within the tubes 4 to the respective compartments 10 and 11 and if all of the dampers 16 and 18 are open, the products of combustion will be distributed within each compartment so as to pass outwardly through all of the openings 6. Thus different utensils can be placed over the respective openings and practically all of the heat utilized for cooking purposes. The smoke and gases will pass outwardly through the opening 12. If an oven is used on the attachment and it is desired to direct the gases and smoke into the walls of the oven, said oven can be placed on the attachment so that the interior thereof will communicate with the two sets of openings 6. In this event the damper 13 is closed and the dampers 16 are likewise closed so as to deflect the hot gases upwardly through the openings 6 adjacent thereto and into the walls of the oven.

Should it be desired to utilize only one pair of openings 6 for cooking purposes, the dampers 18 can be closed.

Under some conditions it is desirable to have a large outlet for smoke or the like into the hollow walls of an oven, for example. This is especially true where the

attachment is used in connection with a wood stove. For this purpose the opening 7 is provided, this opening being normally closed by the sliding damper 8.

What is claimed is:

A heat distributing attachment for stoves including a housing having separate longitudinal compartments, there being an inlet opening in the bottom of the housing at one end and communicating with both compartments and a plurality of outlet openings in the top of the compartments, said housing being provided in one end with a smoke outlet in communication with both compartments, a closure for the smoke outlet, a damper pivotally mounted in each compartment between the outlet and the smoke outlet, there being an outlet slot in the top of the housing between the top outlets, a slide normally closing said outlet slot, means extending from one end of the housing for attaching the device to a stove in position to receive hot products of combustion through the inlet opening, thereby to support one end of the housing beyond the side of the stove, and a warming pan removably connected to the bottom of the projecting portion of the housing.

In testimony that I claim the foregoing as my own, I have hereto affixed my signature in the presence of a witness.

ERASTUS W. ROGERS.

Witness:

HERBERT D. LAWSON.
